CLAIM

The ornamental design for a travel case for an electric
shoe polishing kit or the like, as shown and described.

DESCRIPTION

FIG. 1 is a front, top and left-side perspective view of a
travel case for an electric shoe polishing kit or the like
showing our new design;

FIG. 2 is a front elevational view thereof;

FIG. 3 is a left-side elevational view thereof, the right-

side elevational view being a mirror image;

FIG. 4 is a top plan view thereof;

FIG. 5 is a bottom plan view thereof; and

FIG. 6 is a rear elevational view thereof.

FIG. 1

FIG. 2

FIG. 3

FIG. 4

FIG. 5

FIG. 6
